ILLUMINATING DEVICE FOR TELEPHONES

Filed April 27, 1923

Patented June 15, 1926.

UNITED STATES PATENT OFFICE.

FRANK L. PEYTON, OF DALLAS, TEXAS.

ILLUMINATING DEVICE FOR TELEPHONES.

Application filed April 27, 1923. Serial No. 635,063.

This invention relates to telephone equipment, and refers to an illuminating means in attachment to telephones of the automatic type, whereby the numbers on the dial may be rendered visible when the receiver is removed from the hook.

An object of the invention is the provision of an electric light or lights mounted on the dial post and connected by suitable wiring to the receiver hook wiring, so that when the hook is lifted, the circuit to the lights will be made, and same will illuminate the dial, and when the receiver is hung up the lights will be extinguished.

Another object is to provide a device of this character that may be attached readily and quickly to an automatic telephone, and whose operation and construction is simple and durable.

Another object is the provision of a suitable switch adapted to cut off the current to the lights when it is not desired to use same.

Other objects and features will be set forth in the following description, taken in connection with the drawings attached hereto, as follows:

Figure 1 shows a side elevation of an automatic telephone, with the illuminating device in attachment thereto.

Figure 2 represents a cross-section of the dial, showing the construction of the illuminating dial on the dial post.

Figure 3 shows a detail sectional view of the receiver hook, showing the contact made when same is lifted.

Figure 4 shows a side elevation of an automatic telephone with the invention attached, the dial and the elements of the invention in cross-section, and part of the telephone broken away to show the manner of wiring to the lights on the dial post.

Figure 5 shows a top view of the dial with the invention attached, part being broken away to show the detail of construction of the invention.

Following Figures 1 and 4, the telephone 1, of ordinary construction, rests on base 2, porcelain dial post 13 with metal finger dial 13^a fastened thereon by means 9 and 9^a. Connection is made of wires a—a from contacts 6 and 7, to brushes 10 and 11^a, pre-

erably of copper, and which extend around the dial post 13. To prevent short circuiting of these brushes by the metallic finger 55 dial 13^a a disk of insulating material 14 is interposed therebetween, and for a similar purpose an insulating ring 12 is placed between the brushes themselves. From Figure 2 of the drawing it will be seen, the telephone to which the invention is attached is equipped with a number dial 15 of insulating material; however, should it be desired to attach the device to a telephone having a metallic number dial, it would only be 65 necessary to place another disk, similar to the disk 14, below the brushes 10 and 11^a. Electric bulbs 11 extend through apertures in brush 10, through insulating ring 12, beneath the brush, and contact with brush 11^a 70 on post 13. It will be readily seen that the current must pass through both connecting wires a—a, before the bulbs will be lighted.

The transmitter 3 is shown, and below it the receiver hook 4, supporting the receiver 75 5, as the receiver is lifted from the hook, the operation shown in Figure 3 takes place, namely the contact point on the receiver hook 4, allows spring contact 6 to move forward, and contact with member 7, thereby 80 making a circuit through wires a—a and the battery 8. As this circuit is made, it sends a current through wires a—a, to brushes 11 and 11^a, and through them to light bulbs 10. 15 represents the porcelain 85 lettered dial plate.

It should be understood that a suitable switch may be placed at any convenient point on wires a—a, whereby the current may be switched off from the bulbs, when 90 it is desired to do so.

It should also be understood that the method of construction shown is preferred as it involves less changing of the normal telephone structure, and the least amount of 95 additional structure.

As there is no superstructure on the dial to interfere with the dialing, and very little structure to get out of order, the device is 100 practical for this class of telephone instruments, and is of great advantage where the telephone is located in the dark, or semi-dark rooms, as is frequently the case.

What is claimed is:

1,588,770

In combination with a telephone of the automatic type having a dial plate and an apertured dial therebeneath, an insulating ring and a pair of ring brushes on opposite sides of the insulating ring arranged in nested relation and disposed between the dial and plate, horizontally disposed bulbs extending through the outer ring brush and

connected to the insulating ring, a circuit closer, means to close the circuit closer upon lifting the receiver, and a circuit including ¹⁰ the ring brushes and circuit closer.

In testimony whereof I have signed my name to this specification.

FRANK L. PEYTON.
